UNITED STATES PATENT OFFICE.

SINGLETON VAUGHN, OF BAKERSFIELD, CALIFORNIA.

TRICYCLE.

SPECIFICATION forming part of Letters Patent No. 634,192, dated October 3, 1899.

Application filed February 21, 1899, Serial No. 706,371. (No model.)

To all whom it may concern:

Be it known that I, SINGLETON VAUGHN, a citizen of the United States, residing at Bakersfield, in the county of Kern and State 5 of California, have invented certain new and useful Improvements in Tricycles; and I do declare the following to be a full, clear, and exact description of the invention, such as will enable others skilled in the art to which 10 it appertains to make and use the same.

The invention has relation to tricycles; and the object of the invention is to provide a simple, durable, and inexpensive device of this character by means of which a person 15 while in the act of rocking may propel the vehicle along.

With this object in view the invention consists in certain features of construction and combination of parts, which will be herein- 20 after fully described and claimed.

In the drawings, Figure 1 is a perspective view of my invention, and Fig. 2 is a side elevation of the pawl-and-ratchet mechanism. Fig. 3 is a detail view of one end of the axle 25 and its contiguous drive-wheel. Fig. 4 is a perspective detail view of a portion of one of the elliptical springs and its coacting rocker.

In the drawings, 1 denotes the body of the vehicle, which consists of the framework 2, 30 preferably rectangular in shape and supported at its rear end by the drive-wheels 3 and at its forward end by the steering-wheel 4, which is provided with a pivoted tiller or handle 5 and engages a rack-plate 6. This handle 35 is preferably telescopic, and is held in adjusted position by a set-screw 7.

8 denotes elliptical leaf-springs, the ends of which are connected to the forward and rear cross-pieces of the frame of the vehicle 40 and are located within the side pieces 9 of the vehicle.

10 denotes a yoke fixed to the rear end of the body portion of the vehicle, and 11 denotes a cross-shaft, to which is fixed a sprocket-wheel 12, provided with a ratchet-wheel 13. The sprocket-wheel 12 is connected by a 45 sprocket-chain 14 to the sprocket-wheel 15 on the axle 16 of the drive-wheels, and when the sprocket-wheel 12 is rotated it is evident that 50 the drive-wheels will also be rotated and the velocipede propelled.

As shown in detail in Fig. 3, the drive-

wheels are each provided with a collar 3', to which is pivoted the pawls 3² 3², the free ends of which engage the notched hub 16' of the 55 axle, so as to permit one wheel to turn faster than the other in turning corners and prevent dragging at such points.

In Fig. 4 I have shown the elliptical spring 8 provided with a depending flange 8', to which 60 is secured the lower end of the coiled spring a, the upper end of which is fixed to the rocker, as shown, the object attained being a reaction effect on the chair while in motion.

17 denotes a seat having rockers 18 that engage the elliptical springs before mentioned and are arranged within the side pieces 65 of the body portion.

19 denotes pawls pivoted to the cross-shaft 70 11, one above and the other below said shaft and in engagement with the ratchet-wheel.

20 denotes links connected to the free ends of said pawls and to the rocking seat, so that when the rocking seat is rocked forward one 75 of the pawls will engage the ratchet-wheel and rotate it, and when the seat is rocked rearward the other pawl will engage the ratchet-wheel and continue its rotation in the same direction. Thus by the rocking back 80 and forth of the seat the velocipede is propelled along, and in running over rough ground or obstructions the elliptical springs will relieve shock and jar, thereby adding to the comfort of the occupant.

It will of course be understood that various changes in the form, proportion, and the minor details of construction may be resorted to without departing from the principle or sacrificing any of the advantages of this invention.

Having thus described the invention, what is claimed, and desired to be secured by Letters Patent, is—

In a tricycle, the combination with the supporting-wheels, the steering-wheel, and the body portion supported by said wheels, bowed springs secured at their ends to ledges projecting laterally from the side pieces of the body portion, said springs being provided 95 with downwardly-extending integral plates, coil-springs connecting the intermediate portion of said bowed springs to the rocker, a seat provided with rockers resting upon said 100

bowed springs and inclosed within the side pieces of the vehicle, a sprocket-wheel journaled upon a shaft carried by the body portion and provided with a ratchet-wheel, a 5 sprocket-wheel fixed to the axle of the rear drive-wheels, a chain connecting the two sprocket-wheels, pawls engaging said ratchet-wheel, and links connecting the pawls with the rocking seat, whereby when the seat is 10 rocked back and forth the sprocket-wheels

will be rotated and the vehicle propelled, substantially as and for the purpose set forth.

In testimony whereof I have hereunto set my hand in presence of two subscribing witnesses.

SINGLETON VAUGHN.
